UNITED STATES PATENT OFFICE.

LOUIS SCHULTE, OF CHICAGO, ILLINOIS, ASSIGNOR TO BENNETT-O'CONNELL CO., OF CHICAGO, ILLINOIS, A CORPORATION OF ILLINOIS.

ELECTROPLATING DEVICE.

1,077,646.

Specification of Letters Patent.

Patented Nov. 4, 1913.

Application filed January 11, 1913. Serial No. 741,417.

To all whom it may concern:

Be it known that I, Louis SCHULTE, a citizen of the United States, and a resident of the city of Chicago, county of Cook, and State of Illinois, have invented certain new and useful Improvements in Electroplating Devices, of which the following is a specification.

My invention relates to electroplating devices and more specifically to that class thereof designed for use especially in the electroplating of small articles.

The object of my invention is the production of an electroplating device of the character mentioned through the medium of which the electroplating of metallic articles may be effected economically with ease and expedition.

A further object is the production of an electroplating device through the use of which the cleaning, rinsing, plating, drying and polishing of the metal goods treated may be effected by one succession of operations without necessitating at each step in the process the removal of the goods from the container in which the same are arranged at the commencement of the operation and from which the same are removed after the completion thereof.

30 A further object is the production of a device of the character mentioned which will be of durable and economical construction and of high efficiency in use.

Other objects will appear hereinafter.

35 The invention consists in the combinations and arrangements of parts hereinafter described and claimed.

The invention will be best understood by reference to the accompanying drawings forming a part of this specification, and in which—

Figure 1 is a front elevation of an electroplating device embodying my invention, parts being broken away and shown in section in order to better illustrate the construction. Fig. 2 is an enlarged detail section taken on line $w-w$ of Fig. 1, Fig. 3 is a side elevation of a portion of the container or holder frame included in the construction, Fig. 4 is a section taken on substantially line $x-x$ of Fig. 3, Fig. 5 is a vertical transverse section of the device, Fig. 6 is a view similar to Fig. 5 except that the holder or container is here shown in section, Fig. 7 is a side elevation of a portion of the

frame of the container or holder, Fig. 8 is a top plan view of an electroplating device embodying a modified form of my invention, Fig. 9 is a vertical longitudinal section of the device shown in Fig. 8, Fig. 10 is a vertical transverse section taken on line $y-y$ of Fig. 8, Fig. 11 is a view similar to Fig. 9 illustrating another modified form of the invention, and Fig. 12 is a vertical transverse section taken on line $z-z$ of Fig. 11.

The preferred form of construction as illustrated in the drawings comprises a tank 1 formed of non-conductive material, said tank being open at its upper side. Arranged at the upper edge of the tank 1 is a shaft 2 which is mounted in suitable bearings 3 and 4. Provided at the outer end of the shaft 2 is a pulley 5 adapted for engagement by a belt in driving the shaft 2. Provided at the inner end of the shaft 2 is a gear 6. The gear 6 meshes with an annular internal gear 7 which depends thereto into the tank 1 as clearly shown, the gear 7 resting loosely upon the gear 6, the same being held in mesh with said gear 6 through gravity. The opposite sides of the gear 7 are provided with inwardly extending flanges 8 which serve to hold said gear in mesh with the gear 7, a channel being thus formed. Surrounding the outer side of gear 7 and the corresponding sides of flanges 8 is a covering 9 of insulating material preferably rubber. With the arrangement disclosed it will be seen that upon rotation of the shaft 2 gear 7 will be propelled thereby, the latter being caused to rotate in the tank 1 as will be readily understood.

Arranged centrally in the gear 7 is a holder or container for the articles which it is desired to plate. This holder comprises a hollow, elongated body 10 of non-conductive material such as wood, and a conductive frame formed preferably of metal which consists of the annular angular members 11 which are arranged at the opposite sides of the body 10 and connecting bars 12 which extend between the members 11 at intervals. The members 11 and 12 are so arranged that surfaces thereof will be exposed to the interior of the holder or container and so that in use, articles arranged in the body 10 will contact with said surfaces and thus establish an electrical connection between said articles and the frame of said body. Said body frame is rigidly se-

cured to the gear 7 through the medium of radiating bars 13 also of conductive material, and so that in use the electrical current passing through the goods contained 5 in the holder will pass through the frame members 11 and 12, through the arms 13 and thence through gear 7 and gear 6 meshing therewith to the shaft 2 to complete the electrical circuit as hereinafter described.

10 A section 14 of the peripheral wall of the body 10 is slidably mounted in order to constitute a door for gaining access to the interior of said body, the lateral edges of the section 14 being in dove-tail connection with 15 the adjacent edges of said body, the frame member 11 at one side being cut away as at 15 in order to afford clearance for said section as will be readily understood. The door section 14 is releasably secured in closed 20 position through the medium of a suitable locking device 16. The inwardly extending flanges of the frame member 11, at the opening which is formed upon removal of the door 14 are cut away as clearly shown in 25 Fig. 2 so as to not obstruct said opening.

Arranged in the tank 1 adjacent the upper edge thereof and at either side of the holder or container are bars 17 from which depend anode-forming electrodes 18. Upon bearing 30 3 and corresponding extremities of the bars 17 are binding posts 19 and 20 respectively for connecting the same with a source of electrical energy. The circuit which is thus formed includes the frame members 11 and 35 12 of the holder or container which form cathodes and the electrodes 18 which constitute anodes, said electrodes being electrically connected in order to close the circuit by the electrolyte which is introduced into 40 the tank 1 in the electroplating process and the articles arranged in holder for plating.

In operating the device, the articles which it is desired to plate are first introduced into the holder or container body 10 through the door 14. If it is desired to clean the articles before electroplating, a cleansing liquid is introduced into the tank 1 and the container revolved therein through operation of the shaft 2. After cleansing and rinsing 45 50 of the articles, the container is placed in another tank 1 in which an electrolyte is provided or if desired the same will be permitted to remain in the tank 1 from which the cleansing liquid has been removed and 55 into which the electrolyte has been introduced. The container is then rotated as before in the electrolyte. When this is done it will be seen that the articles resting in contact with the frame members 11 and 12 of 60 the container body will become the cathode in the electrical circuit to which the current will flow through the electrolyte from the anode-forming electrodes 18, thus effecting the plating of said articles as will be readily understood. After the articles have thus

been plated the container may be removed from the tank 1 by disengaging the gear 7 from the gear 6, such disengagement being readily effected since the gear 7 simply rests upon the gear 6 as above described. After 70 the coat or plating has dried upon the articles, the container may be rotated as before in the empty tank 1 in order to effect burnishing or polishing thereof it being clear upon rotation of such container the articles 75 will rub against each other and thereby polish the same as desired.

It is thus seen that with the construction set forth, the entire electroplating process may be carried on without necessitating the 80 removal of the articles treated from the container in which the same are arranged at the commencement of the treatment, the articles being removed from said container only upon completion of the electroplating. This 85 is rendered possible by reason of the detachable arrangement of the container in the tank, said container, where a plurality of tanks are used in the process, being simply removed from one tank and placed in another as will be readily understood. Further with this construction the loss of electrical energy is obviated since with this construction, the circuit is closed upon the insertion of the container in the tank or when 90 gear 7 contacts with the gear 6 and broken when said container is removed from the tank or when the gear 7 is disengaged from the gear 6, the circuit being thus closed only when the container is in operative position. 95 Also with this construction the necessity of a hand operable switch is dispensed with since the breaking and closing of the circuit is automatically effected upon removal or insertion of the container in the tank. 100 105

Numerous other advantages of the construction which it is not necessary here to mention will be apparent to those skilled in the art.

In Figs. from 8 to 10, inclusive, is shown 110 a construction which is a slight modification of that just described. In this construction the container 10 is longer than that of the preferred form and at each end of said container is provided a gear 7 and 115 the parts which coöperate therewith to which the respective ends of said container are connected in the same manner as the gear 7 is connected with the container body 10 in the preferred form. The gears 7 of 120 the modified form mesh with gears 21 which are provided at the respective ends of a shaft 22, which is mounted in suitable bearings 23 provided upon cross pieces 24 which rest loosely upon the upper edges of opposing walls of the tank. The arrangement is such as will be observed that upon rotation of the shaft 22 the container 10 depending therefrom will be rotated in the same manner as the container 10 of the preferred 125 130

form. The removal of the container in the modified form however is effected by engaging the opposite ends of the cross pieces 24 which are formed into grips or handles as shown for this purpose. Rotation of the shaft 22 is secured through the medium of a gear 25 which is fixed to said shaft midway the ends thereof. The gear 25 meshes with a gear 26 provided upon a shaft 27 which is mounted at the free end of a rocking bearing arm 28, the opposite end of said arm 28 being fulcrumed to a shaft 29 which is mounted in bearings 29' provided at the upper edge of the tank 1 as shown in Figs. 8 and 10. The shaft 27 is operatively connected with the shaft 29 through a belt 30 which passes around pulleys 31 provided upon said shafts as shown. The shaft 29 is also provided with a pulley 32 for connection thereof by means of a belt 33 with any suitable source of power supply. With the arrangement disclosed it will be seen that the gear 26 rests loosely in contact with the gear 25, said gears being held in mesh by the weight of the gear 26 and the bearing arm 28, and so that when it is desired to remove the container 10 said arm 28 may be rocked upwardly and outwardly to disengage the gear 26 and permit of lifting of the container out of the tank. The operation of this construction is precisely the same as that above described, anode-forming electrodes 18 being used, which are however arranged along the lateral wall or sides of the container 10 instead of at the ends of the container as shown in the preferred form. In Figs. 11 and 12 is shown a form designed for use especially for electroplating tubes. In this form the construction is the same as that shown in Figs. 8, 9 and 10 except that the container 10 is dispensed with and in lieu thereof a plurality of rings 34 rigidly secured together in annular formation are arranged within the gears 7 rigidly connected with the inwardly extending arms 13. In this construction the tubes to be plated are supported at their respective ends in the rings or holders 34 as shown in dotted lines in said figures, the operation being the same as that above described.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A device of the class described comprising a tank; a shaft journaled adjacent

said tank with a free end projecting partially over the latter; rotary propelling means on the free end of said shaft; a ring loosely suspended in said tank on said propelling means and adapted to be rotated thereby; and a work holding receptacle carried in the opening of said ring, there being sufficient space between the free end of said shaft and walls of said tank to permit the passage of said ring and work holding receptacle into and out of said tank, substantially as described. 70

2. A device of the class described comprising a tank; a shaft journaled adjacent said tank with a free end projecting partially over the latter; a pinion on the free end of said shaft; an internal gear loosely suspended in said tank on said pinion and meshing therewith; annular flanges on said internal gear at the ends of the teeth thereof and extending beyond the latter forming guides; and a work holding receptacle secured concentrically in said internal gear and adapted to be rotated therewith. 80

3. A device of the class described comprising a tank; a shaft journaled adjacent said tank with a free end projecting partially over the latter; a pinion on said free end; an internal gear loosely resting on and in mesh with said pinion and hanging in said tank; spokes in said internal gear; a cathode receptacle carried in said internal gear by the spokes thereof; an electrolyte in said tank engaging said cathode receptacle; an anode suspended in said tank engaging said electrolyte; and an electric circuit including said shaft, pinion, internal gear, cathode receptacle, electrolyte and anode, substantially as described. 90

4. In a device of the class described, the combination of a tank; an electric circuit; rotary propelling means; a cathode-forming holder included in said circuit, there being an electrical connection between said propelling means and said holder through which the current passes when said circuit is completed, said holder being removably arranged in said tank and rotatably and detachably suspended from said propelling means for propulsion by the latter, said holder comprising a non-conductive hollow foraminated body and a conductive frame through which the current passes from said propelling means, surfaces of said frame opening upon the inner side of said body; and anode-forming electrodes arranged in said tank and spaced and insulated from said holder the circuit being completed from said anode-forming electrodes to said cathode-forming holder through the medium of the electrolyte introduced into said tank and the articles arranged in said holder, substantially as described. 100

5. In a device of the class described, the combination of a tank; an electrical circuit; ro- 110

- tary propelling means; a holder removably and rotatably arranged in said tank, said holder comprising a non-conductive hollow foraminated body; a conductive frame for 5 said body, surfaces of said frame opening upon the inner side of said body; an annular conductive member surrounding said body; an insulating covering for said annular member, said annular member loosely resting 10 upon said propelling means for propulsion thereby, the current of said circuit passing from said propelling means through said annular member to said frame of said holder body; and electrodes arranged in said tank 15 spaced and insulated from said holder, the circuit being completed from said electrodes to said holder frame through the medium of the electrolyte introduced into said tank and the articles arranged in said holder, 20 substantially as described.
6. In a device of the class described, the combination of a tank; an electrical circuit; a gear arranged at the upper edge of said tank; a holder rotatably and removably arranged in said tank, said holder comprising 25 a non-conductive hollow foraminated body;
- a conductive frame for said body, surfaces of said frame opening upon the inner side of said body; an annular internal gear surrounding said body and connected with said frame; an insulating covering for the outer side of said gear, said annular gear member loosely resting on said first mentioned gear for propulsion thereby, the current of said circuit passing from said first mentioned gear through said annular gear to said frame of said holder body; and electrodes arranged in said tank spaced and insulated from said holder, the circuit being completed from said electrodes to said holder 35 frame through the medium of the electrolyte introduced into said tank and the articles arranged in said holder, substantially as described.

In testimony whereof I have signed my 45 name to this specification in the presence of two subscribing witnesses.

LOUIS SCHULTE.
